FLY-WHEEL FOR WARPING AND BALLING MACHINES.

958,974.

Specification of Letters Patent. Patented May 24, 1910.

Application filed August 9, 1909. Serial No. 511,842.

To all whom it may concern:

Be it known that I, ALONZO E. RHOADES, a citizen of the United States, and resident of Hopedale, county of Worcester, State of Massachusetts, have invented an Improvement in Fly-Wheels for Warping and Balling Machines, of which the following description, in connection with the accompanying drawing, is a specification, like characters on the drawing representing like parts.

In the treatment of yarn in warping and balling machines the separate threads of yarn are led from spools or the like mounted in a creel-frame to the mechanism which acts upon and pulls the threads forward, to be wound onto a beam in the case of a warping machine or to be wound into a large mass or ball in the case of a balling machine, the creel-frame in either instance being some distance from the draft mechanism. When the latter is stopped by throwing off the power, usually by movement of a shipper, there is apt to be some slackening of the threads between the suddenly stopped mechanism and the creel-frame, due to the fact that the spools have sufficient momentum to turn more or less after the actual draft on the threads ceases. As the threads slacken kinks tend to form, and in the subsequent treatment of the yarn, by a slasher or in dyeing operations, these kinks remain and often form small lumps or enlargements which cause warp breakage in the loom. Such kinks are not necessarily, or usually, pulled out or straightened when the draft mechanism is started up, hence when once formed they are more than likely to remain during subsequent operations on the yarn, as stated.

My present invention has for its object the production of effective governing means for apparatus of the type referred to, whereby when the power is thrown off the draft mechanism the latter will be brought under the control of the governing means and brought thereby to a gradual stop, so that the threads between such mechanism and the creel-frame or similar device are maintained taut enough to prevent the formation of kinks.

For convenience I have shown my invention applied to a warping machine, as therefrom the operation of the governing means can be readily comprehended.

The novel features of my invention will

be fully described in the subjoined specification and particularly pointed out in the following claims.

Figure 1 is a right-hand side elevation of a sufficient portion of a warping machine to be understood with one embodiment of my present invention applied thereto; Fig. 2 is a horizontal sectional detail on the line 2—2, Fig. 1; Fig. 3 is a side view of the balance wheel forming a part of the governing means, with some of the adjacent parts; Fig. 4 is an opposite side view, showing the friction connection between the balance wheel and its actuating shaft; Fig. 5 is a vertical sectional detail on the line 5—5, Fig. 2, looking toward the balance wheel.

In Fig. 1, the driving shaft 1 is provided with the usual fast and loose pulleys, indicated at 2, and in practice there are usually two fast pulleys, for different speeds, the belt being shifted by a suitable belt-shifter or fork 3 partly broken out, these parts forming no novel part of the present invention. A pinion 4 fast on the driving shaft meshes with an intermediate gear 5 mounted on the side frame 6 of the apparatus, said gear in turn meshing with and driving a pinion 7 fast on a transmitting shaft 8 extended across the frame at the back, the mechanism for acting upon the threads to draw them from the creel-frame (not shown) and to wind them onto a beam being actuated from the transmitting shaft 8. None of this mechanism forms any part of my invention herein and for that reason it is not illustrated, as it is old and of well known construction and operation.

From the above description it will be readily understood that if the belt is thrown onto the loose pulley the shafts 1 and 8, and the draft mechanism actuated thereby, will stop quickly, if no means be provided to bring such parts to a gradual stop. I have provided such means and will now describe one practical embodiment thereof.

Upon the shaft 8 at any convenient location, I key or otherwise fixedly secure a ratchet 9 and a radial arm 10, and interpose between such parts the hub 11 of a heavy balance wheel 12, the hub being mounted to rotate upon the shaft. The hub is embraced by a suitable friction coupling, shown best in Figs. 4 and 5 as oppositely curved arms 13 pivoted on the arm 10 at 14 and embracing the hub, the concave parts of said arms being

faced with leather or other suitable material, and said arms are set up as tightly as may be necessary by the clamping device 15. Thus I provide a friction connection or coupling 5 between the transmitting shaft 8 and the balance wheel 12, so that when power is thrown on to the machine the balance wheel will be rotated in the direction of arrow 16, Figs. 1 and 3, solely by or through the operation 10 of the friction coupling. On the outer side of the balance wheel I mount suitable spring-pressed pawls 17 which coöperate with the ratchet 9, it being remembered that the latter is fast on shaft 8. The pawls and ratchet are so arranged that they coöperate when the balance wheel has attained 15 its normal speed after the power has been thrown onto the machine, the balance wheel and shaft 8 then rotating in unison, but until the wheel has reached its normal speed 20 the pawls will click over the more rapidly moving ratchet 9. When the power is thrown off the shafts 1 and 8, the draft mechanism actuated thereby, tends to stop at 25 once, but owing to its momentum the heavy balance wheel 12 will continue to rotate, and as it is positively connected, through the pawls and ratchet with the shaft 8, the latter and the mechanism actuated by it will be kept in motion, but with a gradually decreasing speed, until the energy of the balance wheel is dissipated and the entire apparatus comes to rest. Consequently the 30 parts of the machine which act upon the warp threads and pull them along slow down gradually and come to rest with the threads tight enough to prevent the formation of kinks, because the gradual decrease in the speed of the draft permits the spools to slow down gradually, so that they will not 35 overrun and slacken the threads.

From the foregoing description, taken 40 with the drawings, it will be clear that in starting up and during normal operation of the machine the transmitting shaft 8 and the various mechanisms actuated therefrom are positively driven and controlled, but, when the power is thrown off, said shaft 8 and the mechanisms actuated therefrom will 45 be controlled by the governing means and gradually slowed down by the momentum of the balance wheel. Thus by a simple and effective form of momentum governor I am 50 enabled to obviate the objections pointed out at the beginning of this specification, and without in any way interfering with the proper normal operation of the apparatus 55 as a whole.

When the apparatus is started up it is 60 immaterial that the balance wheel slips on the shaft 8 and lags behind, for said wheel has no function to perform at such time.

The friction connection or coupling is set 65 up only enough to impart gradually the required speed to the balance wheel, as the

function of said connection or coupling extends no further than to put the balance wheel in motion and keep it moving while the power is on the machine.

Various changes or modifications may be 70 made by those skilled in the art without departing from the spirit and scope of my invention as set forth in the claims annexed hereto.

Having fully described my invention, 75 what I claim as new and desire to secure by Letters Patent is:—

1. In apparatus of the class described, a transmitting member, and normally inactive governing means, including a momentum 80 member frictionally connected with and rotated by the transmitting member when the latter is power driven, to assume control of the transmitting member positively and automatically when the power is thrown off 85 and to effect the rotation of said transmitting member at a gradually decreasing speed.

2. In apparatus of the class described, a transmitting member, a driving shaft positively connected therewith, and normally inactive governing means for the apparatus, including a momentum member frictionally connected with and rotated by the transmitting member when the latter is power driven, 90 and a direct and positive connection between the momentum and transmitting members, to continue the rotation of the latter in unison with the momentum member at a gradually decreasing speed when the power 100 is thrown off the driving shaft.

3. In apparatus of the class described, a transmitting shaft, and governing means, including a momentum member frictionally connected with and rotated by the transmitting shaft when the latter is power driven, 105 and a device to positively and automatically connect said shaft and the momentum member to rotate as a unit when the power is thrown off to bring said shaft and the momentum member to a stop gradually and simultaneously as the energy of the momentum member is dissipated.

4. In a warping machine, a transmitting shaft, a balance wheel, a friction coupling 115 between it and the transmitting shaft, to effect rotation of said balance wheel when the transmitting shaft is power driven, and a pawl and ratchet connection between said shaft and balance wheel and operating in the 120 direction of normal rotation, whereby when the power is thrown off the balance wheel acts positively through the pawl and ratchet connection to continue rotation of the transmitting shaft in unison with the balance 125 wheel and gradually bring them to a stop simultaneously.

5. In a warping machine, in combination, a transmitting member, and means, including a momentum member, to assume positive 130

control automatically of said transmitting member when the power is thrown off, continuing the rotation of said member in unison with the momentum member at a 5 gradually decreasing speed and finally stopping the transmitting member.

6. In apparatus of the class described, a transmitting shaft, a radial arm and an adjacent ratchet, fast on the transmitting shaft, 10 a heavy balance wheel having its hub loosely mounted on said shaft between said ratchet and arm, a friction coupling carried by the arm and coöperating with the hub of the balance wheel, and pawls on the latter engaging the ratchet and acting in the direction of normal rotation, said balance wheel 15

being rotated by the transmitting shaft through the friction coupling when the power is on, the stored up energy in the balance wheel acting positively through the 20 pawls and the ratchet fixed on the transmitting shaft to continue the rotation of said shaft with a gradually decreasing speed when the power is thrown off.

In testimony whereof, I have signed my 25 name to this specification, in the presence of two subscribing witnesses.

ALONZO E. RHOADES.
